S. BENENSOHN

POWDER BAG

Filed Nov. 13, 1922

FIG. 1.

FIG. 2.

FIG. 3.

FIG. 4.

FIG. 5.

Inventor
Samuel Benensohn
By himself, a citizen of the
United States.

UNITED STATES PATENT OFFICE.

SAMUEL BENENSOHN, OF CHICAGO, ILLINOIS.

POWDER BAG.

Application filed November 13, 1922. Serial No. 600,526.

To all whom it may concern:

Be it known that I, SAMUEL BENENSOHN, a citizen of the United States, and a resident of Chicago, county of Cook and State of Illinois, have invented certain new and useful Improvements in Powder Bags; and I do hereby declare that the following is a full, clear, and exact description thereof, reference being had to the accompanying drawings, and to the letters of reference marked thereon, which form a part of this specification.

This invention relates to an improvement in powder bags and consists of the matters hereinafter described and more particularly pointed out in the appended claims.

The object of the invention is to provide a small, flat, handy and convenient powder bag which may be easily disposed about the person and which is so constructed that a puff, which is contained within it, will be charged with just sufficient powder for use and will be freed from any excess of powder in the act of withdrawing it from the bag.

With a powder bag of the kind, the puff may be used from time to time without danger of dropping excess powder upon the face or clothing.

The advantages of the invention will appear as I proceed with my specification.

In the drawings:—

Fig. 1 is a perspective view of the powder bag as it appears when folded or closed up.

Fig. 2 is a perspective view showing the powder bag open with parts torn away to show the inside construction.

Fig. 3 is a view representing a section through the bag in a plane indicated by the line 3—3 of Fig. 4.

Fig. 4 is a view representing a vertical section through the bag in a plane indicated by the line 4—4 of Fig. 3.

Fig. 5 is a view representing a transverse section through the bag in a plane indicated by the line 5—5 of Fig. 3.

Referring now in detail to that embodiment of the invention illustrated in the drawings:—10 indicates the bag and 11 indicates the puff contained within the bag. The bag consists of a flat tubular pocket closed at the bottom end 12 and open at the top end 13. The said pocket is of handy size, convenient to be gripped or handled, and is designed to have the top end part 14 folded down upon itself, as shown in

Fig. 1, to bring the bag into small limits of dimension.

The bag is preferably made of an inner bag 15 of chamois skin or the like and of an outer bag 16, which is an ornamental covering for the bag, and may be made of silk, satin, or any other suitable material. The two bags are made so that the one bag fits closely and snugly within the other, as shown in the drawing, the two bags being stitched or otherwise attached together at their top margins, as indicated at 17.

Within the bag is mounted and held a screen pocket 18. This is made of fine mesh of any suitable light wire or other desirable material. Said screen pocket is, as shown, a little more than half the depth of the bag and is somewhat narrower than the width of the bag. It has a closed bottom 19 and an open top end 20, and is designed to receive and retain a flat powder puff 11 made of any suitable material. The screen pocket 18 is secured and held within the bag 10, being stitched or otherwise attached at its upper edge to the inner chamois bag 15, as shown at 21. (See Fig. 4.) Supported and held in this way, there is provided a space 22 surrounding the sides, ends and bottom of the screen pocket,—said space constituting a reservoir to contain powder, as indicated at 23.

The operation of the bag will be manifest from the foregoing. When it is desired to use the powder puff 11, the top end 14, which is normally folded down upon the bag as shown in Fig. 1, is brought to upright position and the bag is opened up, as shown in Fig. 2. This may be readily brought about by pressure upon the side edges of the screen pocket 18, by the fingers of the hand grasping the bag. The fingers of the other hand are then inserted into the bag to grip the puff 11, which is withdrawn from its position in the screen bag through the open top end or mouth of the bag and is then used in the ordinary manner.

The excess powder, deposited on the puff through the wire mesh screen from the powder 23 contained in the reservoir, is scraped off the powder puff as it is withdrawn from the screen pocket, only enough powder remaining on the puff for its efficient use without any excess to drop on the dress or clothing. After the puff has been used it is replaced within the wire screen mesh, the bag is folded again, as shown in Fig. 1,

and is returned to the place where it is worn or concealed. When the puff is in the screen pocket, the engagement between the screen pocket and the puff will act to prevent caking of the powder under the action of the moisture absorbed in the use of the puff.

The powder will normally be deposited to a sufficient extent on the puff without any manipulation of the bag. In case, however, the supply of powder in the reservoir gets low, the bag may be shaken from side to side or may be tapped to distribute the powder over the space occupied by the puff,—the excess being removed when the powder puff is withdrawn, as heretofore described. The inner bag being made of chamois, prevents the powder from absorbing moisture when the bag is carried next to the body.

While in illustrating and describing my invention I have referred to certain details of construction and arrangement of parts, it is to be understood that the invention is not limited thereto except as may be pointed out in the appended claims.

I claim as my invention:

1. A powder bag, comprising a flat tubular bag closed at the bottom and open at the top, and means providing a screen pocket positioned within the bag to leave a reservoir space surrounding said pocket.
2. A powder bag, comprising a flat tu-

bular bag made of flexible material, open at the top and closed at the bottom, a flat tubular screen pocket of fine mesh, closed at the bottom and open at the top, said pocket being secured within the bag with its top edge attached to the opposite sides of the bag in position to leave a reservoir space surrounding its sides and bottom.

3. A powder bag, comprising a flat tubular bag made of flexible material, and consisting of an outer bag of silk or the like and an inner bag of chamois skin, the two bags being attached together at their top edges and being open at the top and closed at the bottom, a flat tubular screen pocket of fine mesh, closed at the bottom and open at the top, said pocket being secured within the bag with its top edge attached to the opposite sides of the chamois bag in position to leave a reservoir space surrounding the sides and bottom of said screen pocket, the main bag projecting above the top of the screen pocket and being adapted to be folded upon itself, and a puff adapted to fit within said screen pocket.

In testimony that I claim the foregoing as my invention, I affix my signature in the presence of two witnesses, this 9 day of November A. D. 1922.

SAMUEL BENENSOHN.
